CLAIM

The ornamental design for an electronic device as shown and described.

DESCRIPTION

FIG. 1 is a front, left, top perspective view of an electronic device.

FIG. 2 is rear, left, top perspective of the electronic device of FIG. 1.

FIG. 3 is a rear, right, top perspective of the electronic device of FIG. 1.

FIG. 4 is a top view of the electronic device of FIG. 1.

FIG. 5 is a left side view of the electronic device of FIG. 1; and,

FIG. 6 is a right side view of the electronic device of FIG. 1.

The even dashed broken lines in the drawings depict portions of the electronic device form no part of the claimed design. The dash-dot broken lines represent boundaries of the claimed design and form no part thereof.

The lighter solid lines denote surfaces and contours. Line shading is not surface ornamentation.
